GARMENT-PATTERN-DRAFTING SQUARE.

Application filed March 13, 1924. Serial No. 698,970.

Our invention relates to a garment pattern drafting square, and has for its principal objects the provision of a relatively simple and practical implement in the nature of a

5 square that may be advantageously used for the drafting of patterns used in the production of ladies', children's, men's and boys' garments; and, further, to provide an implement of the character referred to that will be 10 effective in saving much time and labor on the part of the user in drafting patterns for garments and the like.

With the foregoing and other objects in view, our invention consists in the features of 15 construction and combination and arrangement of parts hereinafter more fully described and claimed, reference being had to the accompanying drawings, in which

Figure 1 is a perspective view of a garment pattern drafting square of our improved construction;

Figure 2 is a top plan view of the front or upper face of the pattern drafting square with a portion of the longer leg or arm 25 thereof broken away;

Figure 3 is a top plan view of the reverse side of the square with a portion of the longer leg or arm thereof broken away.

Fig. 4 is a plan view of a piece of goods 30 with our improved pattern drafting square in position thereon for laying out the pattern of a part of a waist and the square being shown in position so as to obtain certain known measurements for the front neck, the 35 back neck and the arm hole.

Fig. 5 is a plan view of a piece of goods with the pattern drafting square positioned thereon for laying out or drafting the pattern of a two-piece sleeve.

40 Fig. 6 is a plan view of a piece of goods with the pattern drafting square positioned thereon for the purpose of laying out and drafting the pattern for the upper portion of a skirt.

45 Referring by numerals to the accompanying drawings, which illustrate a practical embodiment of our invention, 10 designates the body of the implement which may be formed of any suitable material, such as 50 wood, metal, celluloid or heavy cardboard, said body comprising a relatively long leg or arm 11 and a shorter arm or leg 12. The external corner X between the legs of the square serves as a starting point for all 55 measurements or for the readings of all of

the scales that appear on the faces of the scale body except one. If desired, a small curved brace such as 13 may be arranged across the inner corner of the square.

Appearing on the upper face of the longer 60 leg 11 is a lineal measurement scale 14 that is divided so as to provide inch graduations, the latter being divided into halves, quarters and eighths. For all practical purposes, we prefer to make the longer leg 11 twenty-four 65 inches in length.

Appearing on the face of the shorter leg 12 of the square and extending from a point near the end of the longer leg 11 toward the outer end of said leg 12 is a series of equally 70 spaced marks that form a scale 15 and located on the surface of leg 12 adjacent to this scale are the words "Back neck" and "Scale No. 1". The marks of this scale are numbered consecutively and read from left 75 to right 22 to 52, inclusive, and said scale is used for laying out the back neck portion of a garment pattern.

Appearing on the face of the right hand portion of the shorter arm 12 of the scale 80 is a series of equally spaced marks that form a scale 16 and appearing on the face of the scale body adjacent thereto are the words "Front neck" and "Scale No. 2". The graduations of this scale are marked with the 85 numerals from 22 to 52, inclusive, the same reading from right to left, and said scale is for the purpose of ascertaining the correct measurements for laying off the front neck portion of a garment pattern.

Appearing on the reverse face of the longer leg 11 of the implement and near the left hand end thereof is a series of graduated marks that form a graduated scale 17, and the graduations thereof are sequentially 90 numbered from left to right 34 to 46, inclusive. Appearing on the face of the scale body adjacent to this particular scale are the words "Skirt and trousers" and also "Scale 95 No. 4", this scale being for the purpose of laying off the proper measurements of the hip line for the pattern of a skirt or trousers.

Appearing on the reverse face of the longer leg 11 immediately to the right of the scale 17 is a series of graduated marks 100 that form a scale 18, said marks being sequentially numbered from left to right from 28 to 50, inclusive. Appearing on the face of the implement adjacent to this last mentioned scale are the words "Arm hole" and 110

"Scale No. 3", and said scale is used in laying off the lines and measurement of the arm hole of a garment pattern.

Appearing on the reverse face of the leg 11 to the right of scale 18 is a series of graduated marks that form a scale 19, and said marks are sequentially numbered left to right from 28 to 52, inclusive. Appearing on the surface of the implement adjacent to 10 this scale 19, which is for the purpose of laying off the skirt length of a garment pattern are the words "Skirt" and "Scale No. 5". The last mark of scale 19, or the mark numbered 52, terminates at a point approximately twelve and one-half inches from the corner X, and the remaining right hand portion of the upper surface of leg 11 is provided with a lineal measurement scale graduated to inches, halves, quarters and 15 eighths thereof, and numbered from 13 to 24, reading from left to right.

Appearing on the reverse surface of shorter leg 12 and a short distance to the left of the corner X is a series of graduated 25 marks forming a scale 20, and the marks are numbered from 28 to 50, inclusive, and read from right to left. Appearing on the surface of the square adjacent to this scale 20 are the words "Sleeve" and "Scale No. 7". 30 This scale is for the purpose of laying off the measurements and outline of the pattern for the under portion of a sleeve.

Appearing on the reverse face of shorter leg 12 to the left of the scale 20 is a series 35 of equally spaced marks to form a scale 21, said marks being numbered from 28 to 51, inclusive, and reading from right to left. This particular scale is used for the purpose of laying off the measurements and outline 40 of the pattern for the top or upper portions of a garment sleeve, and appearing on the face of the scale adjacent to said scale are the words "Sleeve" and "Scale No. 6".

Our improved pattern drafting square is 45 particularly designed for drafting patterns for ready-made garments, that is, garments which are made in quantities and in certain sizes, as demanded by the trade, and the use of the square and the numbered scales thereon 50 effect the saving of much time and labor in the laying off of patterns, and the user of the square is not subjected to the necessity of performing any mathematical computations after ascertaining the size of the garment or garments for which a pattern is 55 drafted. For instance, if a pattern is to be drafted for a garment which is designated in trade as a "38", the user of the square after drawing base lines on the sheet from 60 which the pattern is to be prepared places the square in proper position relative to said base lines, with the point X at the starting point, and then marks off on the upright or vertical base line a point coincident with 65 the line on the back neck scale No. 1 that is

marked 38 and the distance from the point X to the mark 38 of the back neck scale doubled, inasmuch as the fabric from which the garment is cut is doubled, gives the proper length for the back of the neck. 70 The user now marks off on the pattern sheet a point opposite line 38 of the front neck scale 16, and the distance from the end Z of the short leg 10 to this last mentioned mark defines the front neck length. The square 75 is now turned over and the point X properly positioned on the pattern sheet and a point is laid off directly opposite the line marked 38 on the arm hole scale No. 3, thus giving the proper point from which the arm 80 outlines may be laid off. With the corner X properly positioned a point is now laid off directly opposite the mark 38 on scale No. 4, thus providing a guide for outlining the hip line of a skirt or pair of trousers. With corner X properly positioned on the pattern sheet, a point is laid off directly opposite line 38 on scale No. 5, thus giving the skirt width. In laying off 85 certain patterns, for instance, the yoke of a skirt, the scales 4 and 5 are used in conjunction with each other. The position of the square is now shifted and with the corner X properly positioned on the pattern sheet a point is laid off directly opposite line 38 in scale 6 to give the width for the top member 90 of a two-piece sleeve. A point is now laid off on the pattern sheet directly opposite the line 38 on scale No. 7, thereby giving the width of the under member of the 95 two-piece sleeve. 100

Thus, in the use of our improved pattern drafting square it is only necessary to know the size of the garment for which the pattern is to be drafted and then by properly placing the square on the pattern sheet and laying off points directly opposite the given number appearing in each scale, the essential and desirable points are quickly and accurately laid off to serve as guides in drafting or laying out the outlines of the different portions of the pattern. 110

In Figs. 4, 5 and 6, we have shown our improved pattern drafting square in position on a pattern sheeting or piece of goods 115 for the purpose of drafting the pattern for a waist, a two-piece sleeve and the upper portion of a skirt. Obviously where a pattern is drafted, it is made in accordance with certain known measurements and certain of the lines of the pattern are marked on the sheet or piece of goods and, with the back neck and front neck measurements known, the square is placed on the pattern sheet with the corner X adjacent to the top of the line 120 representing the center seam of the back and by means of the numbered line on scale No. 1 that corresponds with the back neck measurement, a point can be laid off on the pattern or goods to designate the point between 125 130

the side of the neck opening and the beginning of the shoulder seam.

Without changing the position of the square, the necessary points for laying off the 5 front neck line may be ascertained by means of scale No. 2, the graduated marks of which bear the proper numbers for giving the front neck measurements.

After the back neck and front neck lines 10 have been laid off, the square is shifted inwardly on the pattern sheet or goods with the point X in alignment with the rear edge of the outline of the arm hole and the known measurement for the arm hole opening is 15 noted on scale No. 3, and the point on the pattern sheet or goods adjacent to this mark gives the point to which the depth of the arm hole opening should be made.

To lay off the width of the two portions 20 of a two-part sleeve, the square is positioned as illustrated in Fig. 5 with the point X adjacent to the point where the two sections of materials are to be joined by the inner seam and the known measurement for the 25 width of the inner or under part of the sleeve is noted on scale No. 7, thereby providing a guide for laying off the outline of said inner or under part and in like manner the known measurement for the width of the outer or 30 upper part of the sleeve is noted on scale No. 6, and this point marked on the pattern sheet or pattern to serve as a guide for the cutting of the pattern or sleeve section.

To lay out the pattern of the upper portion 35 of a skirt, the square is positioned as illustrated in Fig. 6, square No. 4 being utilized for obtaining the proper point to lay off the waist line or upper edge of the skirt and square No. 5 for obtaining the line of the 40 seam between the two parts of the upper portion of the skirt.

It will be noted that the graduated marks 45 of all of the scales on both arms or legs of the square terminate at the outer edges of said arms or legs and that all of said graduated scales are readable from the outer corner or point X, with the exception of the

front neck scale 16 which latter is readable from the end Z of arm 10. By virtue of these arrangements, the scale is very readily 50 manipulated while laying off measurements and the graduated or numbered lines of the various scales are easily and quickly read by reason of the fact that they terminate at the outer edges of the arms of the square. 55

A garment pattern drafting square of our improved construction is comparatively simple, may be easily and cheaply produced, saves time, labor and calculations on the part of the user and is very effective in performing its intended functions. 60

The construction of the pattern drafting square as herein shown and described may be varied in minor details without departing from the spirit of our invention, the scope of 65 which is set forth in the appended claim.

We claim as our invention:

A garment pattern drafting square comprising a pair of integrally connected straight edge members disposed at right 70 angles to each other, one of which members is longer than the other, a graduated numbered back neck scale arranged on the shorter one of the straight edge members adjacent to the outer corner formed at the 75 joint between said members, the numbers of said graduated back neck scale reading from left to right, a numbered graduated front neck scale arranged on the same side of the short straight edge member with said back 80 neck scale and arranged between the latter and the outer end of the short straight edge member the numbers of said front neck scale reading in progression from right to left, the graduated lines of said back neck and front 85 neck scales terminate at the outer edge of the short straight edge member, the reverse face of the short straight edge member being provided with graduated numbered top sleeve scale members. 90

In testimony whereof we affix our signatures.
